CLAIM

The ornamental design for an automated material system for 3D printer as shown and described.

DESCRIPTION

1. Automated material system for 3D printer

1.1 : Front

1.2 : Back

1.3 : Left

1.4 : Right

1.5 : Top

1.6 : Bottom

1.7 : Perspective

A new, original and ornamental design for an automated material system, of which is used in 3D printers.
